CARBON HOLDER

Charles A. Fuchs, Hollis, N. Y., and Frank Spaloss, Teaneck, N. J., assignors, by mesne assignments, to Projector Improvement Company, Inc., New York, N. Y., a corporation of New York

Application March 21, 1934, Serial No. 716,558

2 Claims. (CL. 176—119)

This invention relates to carbon electrode holders which form extensions of carbon stumps that are too short to be advanced by the feeding mechanism of lamps in which they are used. It is an improvement over that shown in our application Serial No. 696,336, filed November 2, 1933, in which there is provided a gripping element partially enclosed in one end of a tubular body part to be protected thereby, into which element a reduced shank of the carbon is inserted, and which gripping element is then manipulated, by a finger piece at the other end of the body part, to draw the gripping element in the same direction in which the carbon is inserted to thus cause suitable cams thereon which cooperate with the tubular body part to press resilient jaw members tightly against the shank of the carbon to firmly grip it and thus secure the holder to the carbon.

In the present invention the gripping element, 20 is wholly encompassed by the tubular body part and is pushed, by the finger piece at the opposite end, and in the direction opposite to that in which the carbon is inserted into the holder, and there is provided an interior, annular cam, 25 at the carbon receiving end of the tubular body part, with which the free ends of resilient jaws of the gripping element engage to press them tightly against the shank of the carbon to grip it.

We have observed that where the cam portions 30 or jaw elements project from the tubular body part, they have a tendency to grow or spread in a permanent deformation due to the influence of the heat from the carbon arc. In order that the carbon saver operate efficiently, it must naturally be capable of use close to the carbon arc, the heat of the latter causing deterioration of the resilient jaw elements. But the tubular body part being circularly continuous at its adjacent end, possesses greater strength and adaptability to withstand the heat of the carbon arc, particularly if the wall at said end be thickened. Nevertheless the carbon stick and the carbon saver are of the same diameter and provide a substantially continuous cylindrical surface that can pass through the feed rollers uniformly and evenly.

Features and advantages will hereinafter appear.

50 In the drawing which forms part of the specification,

Figure 1 is a view, partly in section, of a holder attached to a carbon;

55 Figure 2 is a sectional view taken at the line 2—2 of Figure 1;

Figure 3 is a view, partly in section, showing another form of holder attached to the carbon; and

60 Figure 4 is a view, partly in section, of an-

other form of gripping element and finger piece therefor.

Similar reference characters represent similar parts throughout the drawing.

The holder 8 includes a tubular body part 9 having an axially extending aperture 10 at one end 5 into which may be inserted the reduced end 11 formed at the end of a carbon electrode 12. The end or shank 11 of the carbon is received by resilient or bendable arms or jaws 14 extending from a body part 15 of the gripping element 16, 10 with the annular shoulder at the shank in abutment with said body part 15, as shown.

At the inner end of the aperture 10 there is provided an annular cam 17 against which the free ends of the jaws 14 may be thrust by moving the gripping element axially of the body part 9, to thus cause the jaws 14 to tightly grip that portion of the shank 11 which projects into the gripping element. When the gripping element is moved in the opposite direction, the free ends 20 of the jaws 14 move away from the cam 17 and spring away from the shank 11 to relinquish their hold on the carbon for the purpose of replacement.

It will be noted that the tubular passage 10 between the cam 17 and the adjacent end of the body part 9 is of substantial length to afford an ample guide for the carbon shank 11, and also to assure that the jaws 14 will be spaced sufficiently 25 inward in the body part 9 for adequate protection from the heat of the carbon arc. The wall of the body part 9 at the passage 10 is sufficiently thick for ample strength in withstanding the heat of the arc, and in rapidly conducting away 30 the heat at this end of the carbon saver, and to be of the same diameter as the carbon stick 12 in a continuously unbroken cylindrical arrangement therewith. It will be understood that the term carbon saver is used to denote a device 35 which can pass with the carbon as a continuous electrode unit through the rollers of a feeding head in a uniform, constant manner.

To push or pull the gripping element 16 axially of the body part 9 to grip or release the carbon 45 12, there is provided a tubular stem 18 into one end of which extends a reduced portion 19 of the gripping element 16. Said reduced portion 19 is provided with an annular groove 20 into which extend reentrant portions 21 of the stem 18 to 50 form a connection between said stem and the gripping element.

At the other end of the stem there is provided a screw thread 22 which may be on a finger piece 55 23 secured to the stem by a pin 24. The thread 22 of the finger piece 23 engages an internal thread of the body part 9 so that by rotating the said finger piece in one direction the stem 18 is pushed axially and in one direction of the body part 9, and when the finger piece 23 is rotated in 60

the opposite direction the stem with the gripper is pulled axially of and in the opposite direction of the body part.

It will be understood that the gripping element 5 is pulled by the stem due to engagement of the portions 21 with a head 25 at one side of the groove 20. When, however, the gripping element is pushed by the stem 18, the end 26 of the stem engages the shoulder 27 of the gripping element.

10 It will also be understood that connection between the stem 18 and gripping element 16 permits rotation of the stem independently of the gripping element so that the stem may be rotated, after the gripping element has taken hold of the 15 shank 11 and is arrested thereby, to tighten the gripping element on the carbon.

It will further be understood that by this construction the carbon, while being attached to the gripping element, is moved slightly outwardly 20 of the body part 9, thus avoiding any tension on the shank which may otherwise be produced if the carbon were drawn inwardly due to engagement of the shoulder of the carbon against the end of the body part. Consequently the carbon 25 is less likely to break at said shoulder.

In a modified form of the invention the jaws 14a may be formed on the inner tube or stem 18a which is provided with a finger piece 23a and has a pin 30 extending into a cam portion 31 of an 30 L slot having an axially extending portion 32 also. Thus, it will be understood that by rotating the stem in one direction the pin 30 engages one side of the cam slot 31 to push the stem axially of the body part 9a and force the free ends of the 35 jaws 14a against the annular cam 17a and thus grip the shank 11 of the carbon 12. When the stem 18a is rotated in the opposite direction, the pin 30 engages the other side of the cam slot 31 to pull the stem 18a axially of the body part 9a 40 to draw the jaws 14a away from the cam 17a and thus release the carbon. The axially extending portion 32 of the L-shaped slot is provided to permit ready removal and insertion of the stem 18a.

45 In a further modification, illustrated in Figure 4 the gripping element 16b may be formed at one end of the tubular body part 18b, the opposite end being provided with reentrant portions 21b to engage in a groove 20b formed on a reduced portion 50 25b that may be integral with the finger piece 23b.

The outside diameter of the stem 18b of Figure 4 may be smaller than the inside diameter of the body part 9 of Figure 1 and the gripping element 55 may be of larger diameter than the stem and fit into the body part 9 to move freely axially therein. The finger piece 23b is provided with a thread 22b which may engage the internal thread at the end of the body part 9 to cause the free end of the resilient member or jaws 16b to engage 60 the cam 17 to grip the carbon.

Thus, it will be understood that the gripping device and finger piece illustrated in Figure 4 form a cooperative device which may be used with the body part 9 instead of the gripping device and finger piece shown in Figure 1.

65 It will also be understood that the finger piece 23b may be provided with the pin 30 instead of the screw thread 22b for use with the body part 9a of Figure 3.

70 In the preferred mode of operation, the carbon shank is inserted into the saver until the annular shoulder of the carbon abuts the open end of

the saver, whereby the latter and the carbon are maintained in true parallel relation, after being secured together by the clutch. As the length of the annular thickened part of the tube at 10 is relatively considerable, and approximately 5 equal to the diameter of the shank, the carbon may also be maintained aligned with the saver, even if "growth" under heat of the part 10 occurs, because such growth is convergent away from the end of the saver. In any case, however, 10 parallelism, which is the more important factor, is assured by the rigid, true seating of the carbon directly against the one piece tube 9.

While certain preferred embodiments of the invention have been shown and described, it will 15 be understood that changes in the form, arrangements, proportion, sizes and details thereof may be made without departing from the scope of the invention as defined in the appended claims.

We claim:

1. A device including a carbon saver comprising a one piece tube adapted to be engaged by the rollers of a carbon feeding head, said tube having an open end along a plane perpendicular to the tube axis, a carbon electrode of uniform diameter with the tube and having a reduced end shank and having an annular shoulder at the shank lying along a plane at right angles to the axis of the electrode, said tube having the end portion of its wall annularly thickened, said thickened wall portion being of a length approximately equal to the diameter of said shank, the inner end of said thickened end portion having a cam surface, a clutch unit movable along the inside of the tube toward said open end for actuation by said cam surface, said shank being snugly fitted in the thickened tubular portion and being releasably engageable by the clutch unit, said shoulder of the carbon electrode having seating engagement with the thickened tubular portion along said plane for maintaining the carbon electrode parallel to the tube, and the thickened tubular portion, by virtue of the length thereof, tending to align the carbon electrode and the tube irrespective of divergent "growth" of said thickened tubular portion due to heating thereof, and said thickened portion being of uniformly equal outside diameter with the electrode, whereby said electrode and tube can be readily continuously engaged by said rollers. 35

2. A device including a carbon saver comprising a cylindrical tube having an open end lying in a plane perpendicular to the axis of the tube, the wall of the tube adjacent to said open end being internally thickened and providing an internal cam surface, a clutch unit in the tube movable therealong toward said open end for actuation by said cam surface, and a carbon electrode of the same outside diameter as the tube and having a reduced end shank adapted to snugly pass through said thickened wall portion for engagement by the clutch unit, said carbon electrode having a shoulder at the shank, for uniform, true seating with the open end of the tube along said plane, whereby the carbon electrode can be maintained parallel with the tube irrespective of variations in diameter between the carbon electrode and tube, and breakage of the shank by tension caused by the clutch unit is avoided. 60
